UNITED STATES PATENT OFFICE.

WILLIAM L. RIECK, OF KANKAKEE, AND WALTER H. BRETALL, OF OAK PARK, ILLINOIS,
ASSIGNORS TO PARAMOUNT KNITTING COMPANY, OF KANKAKEE, ILLINOIS, A COR-
PORATION OF ILLINOIS.

METHOD AND APPARATUS FOR TURNING HOSIERY.

1,321,944.

Specification of Letters Patent.

Patented Nov. 18, 1919.

Application filed July 20, 1917. Serial No. 181,899.

To all whom it may concern:

Be it known that we, WILLIAM L. RIECK and WALTER H. BRETALL, citizens of the United States, and residents, respectively, of

5 Kankakee, county of Kankakee, State of Illinois, and Oak Park, Cook county, State of Illinois, have invented an Improvement in Methods and Apparatus for Turning Hosiery, of which the following description, 10 in connection with the accompanying drawing, is a specification, like characters on the drawing representing like parts.

This invention relates to a novel method and apparatus for turning hosiery and similar fabric or knitted articles. In the manufacture of such articles as hosiery, it is necessary to turn the article inside out and vice versa for various purposes such as inspection, and in the processes of manufacture 15 such as the singeing process. In some cases the articles are turned while dry, and in other cases while wet, turning in the latter case being the more difficult because of the increased friction due to the wet condition.

25 It is the object of the present invention to provide a simple form of apparatus and an efficient method of operation whereby hosiery or similar articles may be readily and quickly turned when required in the course 30 of manufacture.

It is the object of the invention to provide an apparatus which shall insure the complete turning of the articles from end to 35 end and when required the insertion of a supporting blade into the turned article clear to the end thereof.

It is the object of the invention to provide a simple form of device which may be employed for turning the hosiery or similar articles in which provision is made for engaging and temporarily retaining the closed or toe end while the article is being turned, thus insuring the complete turning of the 45 article.

These and other objects of the invention will appear more fully from the accompanying description and drawings and will be particularly pointed out in the claims.

50 The drawings illustrate a preferred form of apparatus such as would be employed in turning hosiery and positioning it upon the blades of a singeing machine, a preferred form of apparatus or implement for turning

the hosiery inside out as in the course of 55 inspection, and in certain steps of the process of turning.

In the drawings,

Figure 1 is a side elevation partially in vertical cross-section of an apparatus embodying this invention arranged for turning hosiery and simultaneously placing it upon the blades of a singeing machine;

Fig. 2 is a side elevation partially broken away and partially in vertical cross-section 65 of the portion of the apparatus or an implement for turning hosiery;

Fig. 3 is a top plan view of the device shown in Fig. 2;

Fig. 4 is a view similar to the upper end 70 of Fig. 2 showing in addition the toe end of a piece of hose engaged and temporarily retained by the upper end of the device;

Fig. 5 is a view of a portion of the apparatus illustrated in Fig. 1 showing the hose in 75 the process of turning.

An apparatus embodying the present invention may in its preferred form consist of a post provided at its free or upper end with means for engaging and temporarily 80 retaining the closed or toe end of the hose or other article or it may consist of such a post combined with a hose supporting blade and means for moving said blade longitudinally past said post adjacent thereto and 85 upwardly in the general direction thereof.

The latter form of apparatus is shown in Fig. 1 wherein a suitable table or bench 1 shown in cross-section has secured thereto and supported thereby in vertical or upright 90 position the post 2. Adjacent the bench 1 is located a singeing machine of the type disclosed in the patent to George Marshall, No. 1,205,099 granted November 14, 1916. This singeing mechanism being fully disclosed in 95 the said patent and its details of construction not being involved in the present invention, it is necessary here to describe it only in a general way. It includes a supporting frame 3 carrying a horizontal shaft 4 to which power is transmitted in any suitable manner. Upon and radially extending from the shaft 4 is a plurality of arms 5 each of which is provided with a hose supporting blade 6. These blades are of sufficient length to extend from end to end of the hose, are thin and flat and of a slightly arcuate form. When the hose is stretched over

these blades they are carried thereby between the vertically depending burners 7 from which gas flames impinge upon the hose to perform the necessary singeing operation. 5 It will be noted that each blade 6 moves longitudinally past the post 2 adjacent thereto and upwardly in the general direction thereof.

In the description of this apparatus, such 10 terms as "upwardly" are used for purposes of description and not for purposes of limitation for it will be evident that the particular relation of the elements of the apparatus with respect to the horizontal is incon- 15 sequental.

The post 2 shown in side elevation in Fig. 1 is illustrated more in detail in Figs. 2, 3, and 4 of the drawings in its preferred form of construction. Therein it is shown as a 20 hollow metal tube secured at its lower end to a base plate 8 provided with holes 9 by which it may be in turn screwed or bolted to the work bench or table. The upper end of the post is provided with means for en- 25 gaging and temporarily retaining the toe or closed end of the hose.

It is not essential that the post shall be hollow throughout but it is preferably sufficiently hollow at its upper end to form a 30 recess or depression in which is located the means for engaging and temporarily retaining the toe or closed end of the hose. The existence of this hollow or recessed upper end enables the operative more readily to 35 engage the toe or closed end of the hose with the means provided therefor.

These means for engaging and temporarily retaining the article may take various forms. A preferred form consists of a dia- 40 phragm of leather or other suitable resili- ent material extending transversely of the post in the recess at the top and provided with an aperture to catch and temporarily retain the hose. Such a diaphragm is 45 shown at 10 provided with the aperture 11 the periphery of which is serrated by being formed of pointed yielding tongues 12. This diaphragm is conveniently held in position by the construction illustrated. In 50 this construction the post 2 is threaded at 13 near its upper end. A ring or collar 14 in- teriorly threaded is screwed down on the post. The diaphragm 10 is placed inside the ring 14 on top of the threaded portion 55 of the post and then an annulus 15 threaded on its exterior is screwed down in the ring 14 until it abuts against and clamps the diaphragm in place. Holes 16 are provided in the annulus 15 for a spanner.

60 The method of this invention may be understood in its application to the turning of a long knitted stocking although it is applicable to various forms of hosiery and to other similar articles.

65 When the stocking is to be turned in such

processes of manufacture as inspection where it is simply necessary to turn the stocking inside out or vice versa, it would be sufficient to employ the apparatus, a preferred form of which is illustrated in Figs. 70 2, 3 and 4 of the drawing.

The operative takes the stocking 17 pref- erably by the top or open end and draws it down over the post to or near the bottom thereof and works or rubs the leg down 75 until the toe or closed end reaches the top of the post; the operative then pokes with his finger the closed end or toe into engage- ment with the means for engaging and tem- porarily retaining the fabric which in this 80 case is the leather diaphragm provided with the serrated edged central aperture. The fabric being pushed down through the dia- phragm as indicated at 18 in Fig. 4, is en- gaged and temporarily retained thereby. 85 The operative then seizes the stocking by the top or open end now at or near the bot- tom of the post and with one or both hands raises it up over and off from the post pro- gressively turning the stocking. This op- 90 eration is continued until the stocking is completely turned, the extreme or closed end or toe portion being held by the dia- phragm or retaining means until the stock- 95 ing is entirely removed from the post.

This method insures the complete turn- 100 ing of the stocking to the very end or toe portion and enables it to be done quickly and easily even when the stocking is damp or wet.

When the post forms a part of an appa- ratus as when it is used in conjunction with a singeing mechanism such as illustrated in Fig. 1, the earlier steps of the method are similar to those described. Referring to 105 Figs. 1 and 5 of the drawing, the operative, after drawing the stocking down over the post and inserting the closed or toe end into the retaining means at the top of the post, then, as the supporting blade 6 moves longi- tudinally past said post adjacent thereto and upwardly in the general direction there- 110 of, seizes the open end of the stocking at or near the bottom of the post and raises it up off the post and in one movement over onto the free end of the moving blade; the op- erative retains the open end of the stocking in his hand and thus permits the moving blade to enter the stocking and by its move- 115 ment simultaneously to withdraw the stock- ing turned from the post, the toe or closed end of the stocking being retained in its en- gagement at the top of the post until the stocking is otherwise free of the post, thus insuring the entry of the blade clear through the turned stocking to the closed or 120 toe end thereof.

By this method the stocking is not only completely turned from end to end but the blade enters it clear through to the toe or 130

closed end thus insuring the singeing of the stocking throughout its entire area.

When an apparatus such as that illustrated in Fig. 1 is employed and when the 5 method such as that last described is employed wherein the stocking is turned from off the post and simultaneously placed upon a moving blade, such as that of a singeing mechanism, still greater economy of operation results and in fact the entire operation 10 of both turning the stockings and placing them upon the blades can be performed as rapidly and easily by the operatives usually required to do nothing but place the stockings after they are turned upon the blades.

It is to be understood that the construction disclosed herein is illustrative but not 15 restrictive and that the same may be modified within the meaning and scope of the 20 claims which follow.

Having fully described our invention, what we claim as new and desire to secure by Letters Patent, is:

1. The method of turning hosiery by the 25 use of a post provided with a recessed top having means for engaging and temporarily retaining fabric therein which consists in passing the hose open end down over the post until its closed or toe end is adjacent 30 the top of the post; pushing the said closed or toe end into engagement with said engaging and temporarily retaining means; seizing the open end of the hose and passing it up off the post thus turning the hose; and 35 continuing the upward movement of said open end until the closed or toe end is pulled off from engagement with said temporarily retaining means whereby the hose is completely turned from end to end.

2. The method of turning hosiery which 40 consists in passing the hose open end down over a post until the closed end is adjacent the top of the post; temporarily engaging the said closed end with the top of the post; 45 moving a supporting blade longitudinally past said post adjacent thereto and upwardly in the general direction thereof; seizing the open end of the hose; passing said open end up off the post and over onto the free end 50 of said blade as it moves; retaining said open end and thus permitting said blade to enter the hose and simultaneously to withdraw it turned from the post, the closed end being retained by the post until the hose is otherwise 55 free of the post, thus insuring the entry of the blade clear to the closed end of the turned hose.

3. The method of turning hosiery by the 60 use of a post provided with a recessed top having means for engaging and temporarily

retaining fabric therein which consists in passing the hose open end down over the post until its closed or toe end is adjacent the top of the post; pushing the said closed or toe end into engagement with said engaging and temporarily retaining means; moving a supporting blade longitudinally past said post adjacent thereto and upwardly in the general direction thereof; seizing the open end of the hose; passing said open end up off the post and over onto the free end of said blade as it moves; retaining said open end and thus permitting said blade to enter the hose and simultaneously to withdraw it turned from the post, the closed end 65 being retained by the post until the hose is otherwise free of the post, thus insuring the entry of the blade clear to the closed end of the turned hose.

4. A hosiery turning apparatus comprising 70 an upright post provided at its upper end with means for engaging and temporarily retaining fabric; a hose supporting blade, means for moving said blade longitudinally past said post, adjacent thereto and upwardly 75 in the general direction thereof, whereby hose drawn over said post with its toe end in engagement with said engaging and temporarily retaining means, when seized by its lower open end and passed up off the post 80 and over onto the free end of the moving blade, will be completely turned from end to end and entered clear to the closed end by the said blade.

5. A hosiery turning apparatus comprising 85 an upright post, means for securing said post to a table or bench, a recess in the upper end of the post and means located in said recess for engaging and temporarily retaining fabric, and permitting disengagement of 90 the fabric by a pull upon the fabric.

6. A hosiery turning apparatus comprising 95 an upright post, means for securing said post to a table or bench, a recess in the upper end of the post, and a centrally apertured 100 transverse resilient diaphragm located in said recess and adapted to engage and temporarily retain fabric.

7. A hosiery turning apparatus comprising 110 an upright post, means for securing said post to a table or bench, a recess in the upper end of the post, a resilient diaphragm provided with a serrated edged central aperture, and means for clamping said diaphragm to said post transversely thereof 115 and in said recess.

In testimony whereof, we have signed our names to this specification.

WILLIAM L. RIECK.

WALTER H. BRETALL.
